UNITED STATES PATENT OFFICE.

HENRY A. WISE WOOD, OF NEW YORK, N. Y., ASSIGNOR TO THE WOOD NEWSPAPER MACHINERY CORPORATION, OF NEW YORK, N. Y., A CORPORATION OF VIRGINIA.

DEVICE FOR DELIVERING STEREOGRAPHIC PRINTING PLATES AND TAILS FROM A FINISHING MACHINE.

1,418,417.

Specification of Letters Patent. Patented June 6, 1922.

Original application filed October 17, 1912, Serial No. 726,239. Divided and this application filed January 14, 1920. Serial No. 351,366.

To all whom it may concern:

Be it known that I, HENRY A. WISE Wood, a citizen of the United States, residing at New York, in the county of New York and State of New York, have invented a new and useful Device for Delivering Stereotype Printing Plates and Tails from a Finishing Machine, of which the following is a specification.

10 This is a division of my Patent No. 1,341,608, granted on an application Serial No. 726,239, originally filed Oct. 17, 1912.

This invention relates to the production of curved stereotype printing plates in condition ready to be applied to the press.

15 The principal objects of the invention are to provide a machine in which practically no hand labor will be required in handling the severed tails which ordinarily are retarded to the melting pot, and also to provide means whereby the plates are retarded as they pass down an inclined runway and the tails cut off the plate in the finishing mechanism will be delivered by gravity and arranged by gravity in proper position to be taken up by a conveyor and delivered back to the melting pot, and other improvements in details of construction and combinations of parts as will appear hereinafter.

20 Reference is to be had to the accompanying drawings in which—

Fig. 1 is a front elevation of a machine constructed in accordance with this invention;

25 Fig. 2 is a plan of the same;

Fig. 3 is a perspective view of a part of the riser conveying chain;

Fig. 4 is a front view partly in central longitudinal section showing the connection between the casting cylinder and finishing mechanism;

Fig. 5 is an enlarged view of a portion thereof;

Fig. 6 is a fragmentary end view thereof;

40 Figs. 7, 8, 9 and 10 are end views showing four positions of the parts during the operation of clamping the plate in the arch and delivering the tail;

Fig. 11 is a side elevation of the parts shown in Fig. 10, and

Fig. 12 is a view of a portion of the ma-

chine looking down on the same normally to the path of the movement of the plate therethrough.

In my Patent No. 1,269,239, granted June 11, 1918, I have shown a machine in which the finishing operation is performed in such a way that the plate is fed through the finishing means by the action of gravity, thus eliminating most of the labor of handling the plate during this operation without materially adding to the amount of power required for this purpose. The present invention involves the use of this principle, but in addition thereto the disposal of the severed tails.

Referring first to Figs. 1 and 2, the machine is illustrated as supported by a framework A which is provided at a distance above the floor with a platform B for the operator which is reached by means of steps, or the like. On the frame are arranged in inclined position and substantially in alignment with each other a casting mechanism C, and a finishing mechanism D. A cooling mechanism E is supported by the frame A also, at the end of the finishing mechanism. At one side of the frame near the casting mechanism is a receiver for the severed tails shown in the form of a melting furnace F. Extending from the finishing mechanism to this furnace is an arrangement G for transferring the tails or risers removed from the plates to the furnace for remelting.

The furnace and casting mechanism are driven by a motor K. This motor through suitable gearing drives a shaft which in turn drives the stirrer of the melting pot, which forms a part of the furnace. The melting furnace, as usual, has a pump operated by a handle H.

It will be obvious that an inclined runway is provided parallel with the direction of the axis of the finishing mechanism. Therefore the plate is free to slide down the runway. For the purpose of retarding this motion and keeping the movement of the plate under the control of the operator, while moving into the finishing mechanism, a retarding means is provided comprising in this instance a pair of toothed wheels 80 in position for the teeth thereof to engage in

the teeth of the rack r on the plate which moves down the inclined runway. These wheels also assist in supporting the plate at this time. Each wheel is provided in the 5 face thereof with a series of inserts 82 for affording a friction surface. These preferably are formed of cork. Adapted to bear against the faces of these wheels is a movable member 83 provided with similar 10 inserts 82^a. Two studs 84, on which the wheels are mounted to rotate are provided on a bracket 81. The member 83 is pivoted to an arm of a lever 85 which is pivotally mounted on the bracket 81 on the frame of 15 the machine. The other end of this lever is pivotally connected with an adjusting screw 86 which is tapped into the frame A. The screw is provided with a collar stud 87 for the reception of the end of the lever and 20 with a hand wheel 88 by which it is adjusted. In this way it will be seen that the friction can be adjusted readily, and although gravity is depended upon for conveying the plate down the incline, the motion 25 of the plate is entirely within the control of the operator.

The plate is fed down in this way under the control of the operator to the shaving arch of the finishing mechanism D, and 30 while there the plate is clamped, rotated, and shaved in the manner indicated in my Letters Patent on a "Machine for finishing and cooling stereotype printing plates" No. 1,238,973 dated Sept. 4, 1917, or in any other 35 desired way. At this time also the tail is cut off the plate by means of a moving rotatable saw 90 which also is operated in accordance with the principle set forth in the above identified patent or otherwise as may 40 be desired.

The shaft 1 carrying the shaving knife 11 is provided with a tumbling pulley 2 mounted thereon and adapted to support the tail T as it is sawed from the main part of the 45 plate. This pulley is of segmental form and the tail is kept from the top of the saw 90 by lugs p cast on the inner side of the tail in position to contact with the edge of the pulley. This stops the plate in proper position 50 for the planetary saw 90 to screw the tail. This pulley is loosely mounted on the shaving shaft and is rotated with it part of the time by a driving pin 4 fixed on the shaving shaft engaging in an arcuate slot 55 formed in the web of the pulley. The beginning of the operation is shown in Fig. 7 in which the plate P is being clamped in the shaving arch D by the means shown in my above mentioned application, and the tail 60 T is supported on a projection 7 formed eccentrically on the tumbling pulley for this purpose. One edge of the plate rests on a guide 8 attached to the arch and the other rests on a pivoted receding track 9 as shown 65 in my above identified patent. The shaving

shaft and the tumbling pulley are at rest in this position of the parts. The driving pin 4 is engaged in the slot 5 at one end holding it from moving in the direction of the arrow in this figure. The rotary cutter 90 is indicated in dotted lines. Now assuming the shaving shaft to rotate in the direction of the arrow (Fig. 7) it moves the pin to the other end of the slot, and therefore picks up the tumbling pulley after the shaft is 70 turned through a part of a revolution so as to bring the tumbling pulley against the end of the tail. The plate in the meantime has been forced up into the arch by the movement of the track 9. The saw 90 moves of 75 course with the shaving shaft, and the parts are now in the position shown in Fig. 8.

The next position of the parts is shown in Fig. 9 in which a projection 10 on the pulley engages the rear edge of the tail and acts to 80 positively move it with the shaft. Fig. 10 indicates how the tail is dropped from the tumbling pulley after the saw has completely severed it. The tumbling pulley constitutes the sole support of the tail as 85 soon as the saw passes from it at the right side of Fig. 9. The projection 10 on the side of the pulley engages the edge of the tail and as the shaft rotates, moves the tail around with the plate, but when it is rotated 90 far enough for more than half of the weight of the tail to be on the right side, then the weight of the tail turns the loose pulley and brings the parts into the position shown in 95 Fig. 10, the pin 4 coming then at the other 100 end of the slot. Then the tail is free to fall away from the pulley by gravity and is deposited on the chute 91 concave side up.

When the tails are dropped in the chute 91 they descend through it into engagement 105 with an inclined platform 92. It will be seen that they lie in the chute in a direction with their axes parallel with the general direction of motion of the plate through the casting mechanism. When they engage the 110 platform 92 the weight of the tails acted on by gravity causes the tails to be turned so that their axes are parallel with the direction of an endless conveyor 93. This conveyor is operated by a motor K² and is provided with a series of projections 94 on the chain thereof which engage the rear edges 115 of the tails and convey them up the inclined conveyor trough 95 to a platform 96 above the melting pot F from which they can descend through a chute 97 into the melting pot. It will be understood also of course 120 that plates to be remelted can be deposited on the conveyor by hand or otherwise and moved in the same way into the melting pot 125 or other receiver for the metal. The stereotype plate disclosed is not claimed herein as it forms the subject matter of my co-divisional application thereon filed on even date herewith.

It will be understood, of course, in accordance with my above mentioned Patent 1,238,973, that while the tail is being cut from the plate the interior also has been shaved out by the shaving blade and the front edge trimmed up if desired. While these operations are performed the chips collect on an inclined surface 12 and are stopped by a plate 13 located at the bottom of the same to direct them into any convenient position. The plates being released then from the shaving arch by the operation of the treadle H^e slide down the incline on a horizontal track 14 constituting the support for the plates of the cooling trough E.

Although I have illustrated and described the machine in detail, I am aware of the fact that the principles herein involved can be carried out with other forms of mechanism, and especially other forms of finishing mechanism, without departing from the scope of the invention as expressed in the claims, and I am also aware that any mechanism shown herein which is similar to that described in my previous applications and patents above identified can also be changed within the scope of this patent. Therefore I do not wish to be limited in these respects, but

30 What I do claim is:—

1. In a stereotype plate machine, the combination of an inclined runway, means for retarding the descent of a cast plate along the runway, a receiver, means for directing the tails and the plates in different paths, and means for catching the tails and moving them back upwardly to the receiver.

2. In a stereotype plate machine, the combination of a receiver, means for directing the tails and the plates in different paths, and means for catching the tails and moving them back to the receiver.

3. In a stereotype plate machine, the combination of a receiver, means for directing the tails and the plates in different paths, a trough for receiving the tails from the tail removing means, and an elevator connected therewith for moving the tails upwardly to the top of the receiver.

50 4. In a machine for making stereotype printing plates, the combination of means for directing the tails and the plates in different paths, a receiver, means for receiving the cut tails, an endless chain conveyor in position to engage the tails and having projecting members thereon for engaging said tails, and means for operating said conveyor to raise the tails up an incline to the top of said receiver.

60 5. In a machine for making stereotype printing plates, the combination with a receiver, of means for delivering the cast plate, means for directing the tails and plates in different paths, means for receiving the tail at the side, and a conveyor movable in

a direction transverse to the direction of the plate through the last named means and into position to engage the tail and move it into a position over the receiver.

6. In a stereotype plate finishing machine, 70 the combination of means for receiving the tails directly from a machine, a platform in position for receiving the tails and changing the direction of the axes thereof, and a conveyor in position to receive the tails and 75 convey them in the direction in which their axes lie after engaging said platform.

7. The combination with a melting pot, of means for receiving tails cut from curved stereotype printing plates, a conveyor arranged to move transversely to said means, and means adjacent to the conveyor for moving the tails to bring their axes into line with the direction of motion of the conveyor. 80

8. The combination with a melting pot, of means for receiving tails from curved stereotype printing plates, a conveyor arranged to move transversely to said means, means adjacent to the conveyor for moving 90 the tails to bring their axes into line with the direction of motion of the conveyor, and a platform over the melting pot for receiving the tails from the conveyor.

9. The combination with a receiving pot, 95 of a conveyor for raising solid metal to the pot, and a chute for delivering solid metal articles to the bottom of the conveyor by gravity, said chute comprising means for turning the metal pieces while descending 100 therein into position to be received longitudinally by said conveyor.

10. The combination with a receiving pot, of an endless conveyor for raising metal to the pot, a support for cast plates and a chute 105 for delivering the cast plates from the support to the bottom of the conveyor by gravity, said chute having means for turning the cast plates while descending therein into position to be received longitudinally by the 110 conveyor.

11. The combination with an upwardly inclined conveyor, of an inclined bottom therefor, and a chute having an inclined bottom in the same plane as the inclined bottom of the conveyor, and having means for delivering curved tails on its inclined bottom in a longitudinal position at an angle to said bottom of the conveyor. 115

12. The combination with an inclined conveyor, of an inclined bottom therefor, and a chute having an inclined bottom in the same plane as the inclined bottom of the conveyor, having means for delivering curved tails on its inclined bottom in a pre-determined position, and a support for the tails at the top of said chute. 120

13. The combination with an inclined support for stereotype printing plates, and a pot for supplying metal to the mold in which 130

the plates are cast, of means for receiving the severed tails from said inclined support and introducing them into the pot.

14. The combination of an inclined runway adapted for supporting curved plates on their convex backs and feeding them down it by gravity and having means for turning them therein but keeping them in

a position in which they rest on said backs, with an elevator located in position at a horizontal angle thereto for taking the plates up another incline from the last named position while still resting on said backs.

In testimony whereof I have hereunto affixed my signature.

HENRY A. WISE WOOD.
